US00D752554S

(12) **United States Design Patent**
Valeur

(10) **Patent No.:** **US D752,554 S**
(45) **Date of Patent:** **** Mar. 29, 2016**

(54) **REMOTE CONTROL**

(71) Applicant: **BANG & OLUFSEN A/S**, Struer (DK)

(72) Inventor: **Torsten Valeur**, København V (DK)

(73) Assignee: **Bang & Olufsen A/S**, Struer (DK)

(**) Term: **14 Years**

(21) Appl. No.: **29/503,203**

(22) Filed: **Sep. 24, 2014**

(30) **Foreign Application Priority Data**

Mar. 24, 2014 (EM) 002431155
